UNITED STATES PATENT OFFICE

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,853**, dated September 2, 1873; application filed August 9, 1873.
[Term of Patent 3½ years.]

a.

To all whom it may concern:

Be it known that I, FREDERICK WINK, of the city and county of Philadelphia, State of Pennsylvania, have invented a Design for Shawl-Pattern, of which the following is a specification:

The principal features of my design, which is fully illustrated by the figure in the accompanying drawing, are the parallel stripes A and B upon a plain ground, D. The stripe A is the narrowest, and has a central bar, a, ornamented by shaded dots and shaded oblong dashes, as shown, there being at either side of this bar shaded ribs b e d e, &c., and strongly-contrasted ribs of different widths and shades

or colors at the edges of the stripe. The wide stripe B has a plain center and a bar, f, near each edge similar to the bar a of the stripe A, it being otherwise composed of plain parallel ribs, arranged as shown.

Irrespective of the colors employed, I claim—

The design for a shawl-pattern, as described, and represented in and by the accompanying drawing.

In testimony whereof I have signed my name to this specification in the presence of two subscribing witnesses.

Witnesses: FRED. WINK.

CLINTON M. LATOURETTE,
LEWIS T. GODFREY.
